Fig. 6a.

Technical drawing showing a cross-section of a mechanical assembly. The drawing includes a vertical scale on the left with markings 63, 70, 72, and 77. A horizontal scale at the bottom has markings 63° and 70°. A vertical dimension line on the right indicates a height of 63°. The assembly features a base with a slot, a central vertical component, and a top part with a hatched area.

Fig. 3. 65

Technical drawing of a cross-section of a component labeled 'Fig. 6.' The drawing shows a stepped profile with various dimensions labeled: 59, 63, 68, 63, 70, 63a, 63b, 71, 72, and 71. The drawing includes hatching and cross-hatching to indicate different materials or features.

25

A cross-sectional diagram of a composite structure. It consists of a central vertical column with a horizontal top and bottom. The top layer is labeled 67. Below it is a hatched layer labeled 68. The central column is labeled 69. At the bottom, there are two layers: 70 on the left and 71 on the right. The bottom-most layer is labeled 72. To the left of the structure, the numbers 63 and 64 are written vertically. To the right, the numbers 65 and 66 are written vertically.

LOOM HAVING MEANS FOR SEVERING TUFT FORMING STRANDS

Joe K. McCutchen, Ellijay, and David A. Tillman,
Cartersville, Ga.

Application July 28, 1950, Serial No. 176,301

13 Claims. (Cl. 139—291)

1

The present invention relates to looms and has particular reference to means for severing tuft-forming strands or threads which are woven in the fabric for producing lines of tufting.

An important object of the invention is to provide means which will sever the floating strands while the loom is in operation, at the longitudinal center of the strands for producing an even or uniform line of tufting.

A further object of the invention is to provide a presser foot which will hold the fabric flat at the time that the prongs pass beneath the floating strands.

Other objects and advantages of the invention will be apparent during the course of the following description.

In the accompanying drawings, forming a part of this application, and in which like numerals are employed to designate like parts throughout the same,

Figure 1 is a plan view of apparatus embodying invention, showing the same applied to a loom,

Figure 2 is a side elevation of a presser foot, removed,

Figure 3 is a plan view of the presser foot, the vertical arm being shown in section,

Figure 4 is a longitudinal section taken on line 4—4 of Figure 3,

Figure 5 is a similar view taken on line 5—5 of Figure 3,

Figure 6 is a transverse section taken on line 6—6 of Figure 3,

Figure 6a is a similar view taken on line 6a—6a of Figure 3,

Figure 7 is a plan view of the carriage and associated elements.

Figure 8 is a side elevation of the same,

Figure 9 is an end elevation of the same, associated elements being shown in section.

Figure 10 is a vertical section, taken on line 10—10 of Figure 8,

Figure 11 is a central vertical section through the coupling element for securing the chain to the carriage,

Figure 12 is a diagrammatic view of the loom and strand-severing means,

Figure 13 is a diagrammatic view of the fabric and presser foot.

Figure 14 is a longitudinal section through the fabric, and

Figure 15 is an enlarged vertical longitudinal section through one prong, passing beneath the floating portions and showing the severing action.

In Figures 1 and 12, the numeral 20 designates the breast beam of the loom. Arranged beneath

2

the breast beam in the sand roller 21 and 22 is a pick-up roller. The numeral 23 designates the lay and 24 are the heddles which form the shed. Numeral 25 is the warp beam and 26 is a guide roll. This is the conventional loom. The numeral 27 is a fabric being woven.

The means which severs the tuft-forming strands comprises horizontal guide means or track rails 28, extending transversely of the loom, near and spaced from the breast beam 20, and arranged at an elevation above the breast beam. These track rails are supported at their ends upon the loom sides by uprights 29. These track rails may be in the form of L irons.

10 Mounted to travel upon the track rails 28 is a reciprocating carriage 30, embodying a vertical plate 31, having upper horizontal axles 32 rigidly secured thereto, adjacent to its top and opposite ends. The axles 32 carry wheels 33, rotatable

15 thereon, travelling upon the track rails 28. Lower transverse axles 34 are rigidly secured to the vertical plate 31, and correspond in number and arrangement to the axles 32 and carry rotatable wheels 35. The wheels 35 are in vertical alignment

20 with the wheels 33 and are arranged beneath the horizontal webs of the track rails 28 and are spaced therefrom. The function of the wheels 35 is to prevent undue vertical movement of the carriage with respect to the track rails 28. A horizontal guide rail 36 is provided to engage the ends of two of the wheels 33, and the guide rail is mounted upon the top of one track rail 28, and is adjustably secured to brackets 37 by bolts 38. The brackets are secured to the track

25 rail 28, as shown. Arranged near the right end of the track, Figure 1, which is the starting or idling position of the carriage, Figure 1, is the leaf spring 39, mounted upon and attached to one track rail 28 and adapted to receive one wheel

30 33 between it and the track rail, when the carriage is shifted to the starting or idling position, thereby securely detachably holding the carriage in the starting or idling position.

In order that the carriage and the severing means to be described will keep up with the travel of the fabric as it is being woven, the track rails 28 and the guide rail 36 are inclined slightly in a horizontal plane, their left ends being slightly in advance of their right ends and these right ends are at the starting or idling position of the carriage. The inclination will vary depending upon the speed of operation of the loom and the speed of travel of the carriage. The carriage must be shifted laterally in a forward direction to keep up with the travel of the

35

40

45

50

55

fabric as it is being woven, so that the cutters will sever the floating portions at the longitudinal centers of such floating portions.

The vertical plate 31 of the carriage depends below the axles 32 and 34 and is provided with a bracket 40 rigidly secured thereto by bolts 41 or the like. Opposite the brackets 40, the plate 31 has a large opening 42, receiving a tubular hub 43, formed upon a large gear 44. Arranged within the bracket 40 is a sprocket wheel 45, having a tubular hub 46. The tubular hub 46 fits within the tubular hub 43 and is rigidly secured thereto by means of a press fit or the like. Ball bearings 47 are arranged within the telescoping tubular hubs and are mounted upon a horizontal shaft 48, rigidly secured to the bracket 40. A lower horizontal shaft 49 is rigidly secured to the lower end of the vertical plate 31, and carries ball bearings 50, the outer races of which have a press fit within a sleeve 51, which is accordingly rotatable upon the shaft 49. This sleeve is provided at its end adjacent to the vertical plate 31 with a radial flange 52, to engage with a cylindrical rotary cutter 53, having a central opening to receive the sleeve. A second cylindrical rotary cutter 54 is provided having a central opening to receive the sleeve 51 and a spacer 55 is arranged between the rotary cutters. The pin or pins 56 are attached to the flange 52 and pass through openings in the rotary cutters 53 and 54. A clamp ring 56' has screw threaded engagement upon the sleeve 51 and is adapted to be screwed up into engagement with the adjacent rotary cutter 54, to clamp the rotary cutters to the spacer 55 and the cutter 53 to the flange 52. A small gear 57 is rigidly secured to one end of the sleeve 51 by means of a press fit therein or by any other suitable means. The gear 57 is rotatable upon the shaft 49 and is rigidly secured to the sleeve 51 and this small gear engages the large gear 44.

Arranged adjacent to the lower edge of the rotary cutters 53 and 54, is a horizontal presser foot 58 rigidly secured to the vertical arm 59, secured to a depending portion 60 of a plate 31 by bolts 61, passing through slots 62. The arm 59 may therefore be vertically adjusted and clamped to the depending extension in the selected adjusted position. The presser foot 58 is horizontal and includes a body portion 58' which carries laterally spaced horizontal fingers 63 and 63' integral therewith. The fingers 63 and 63' are provided at their forward ends with lower rounded or inclined portions 64. The fingers 63 and 63' form a space, or recess, 65, and the presser foot 58 has an inclined or rounded face 68', at the rear end of the recess 65. The lower face 63' of the finger 63 is at an elevation slightly above the lower face 63^b of the finger 63', Figure 6. The finger 63 travels over the unsevered floating portions 27^d, while the finger 63' travels over the severed floating portions, and shifts the severed floating portions out of its path of travel and hence the finger 63' travels close to the fabric base. The body portion 58' of the presser foot 58 is provided upon its bottom with a recess 67, receiving a horizontal plate 68, secured to the presser foot 58 by screws 69 or the like. The plate 68 has a pair of spaced horizontal prongs 70, formed integral therewith. The bottom edges 71 of these prongs is at an elevation beneath the bottom face of the plate 68 and the bottom faces 63^a and 63^b of the fingers. The bottom faces 71 are flat, as shown. The prongs 70 are positioned within the recess 65 and are equidistantly spaced from each other and from the arms 63. The up-

per faces 70' of the prongs at their forward ends are curved in cross section and are convex and are also vertically inclined longitudinally, extending upwardly in a rearward direction. The prongs are provided at their rear ends with upper longitudinal grooves 72, which also extend into the plate 68. These grooves have their bottoms circularly curved longitudinally and transversely. The rotary cutters 53 and 54 have their edges operating within the grooves 72 but are slightly spaced from the bottoms of the grooves, Figure 15.

Means are provided to reciprocate the carriage 30, comprising an inner sprocket chain 73, engaging about a sprocket wheel 74, at its forward end, carried by shaft 75, mounted in stationary bearings 76. This sprocket chain, at its starting or rear end, engages about a sprocket wheel 77, rigidly mounted upon a shaft 78, journaled in a bearing 79, carried by a horizontal arm 80 mounted upon a suitably supported gear box 81. The shaft 78 is driven by gears within the gear box, or it may be driven by other means. The sprocket wheel 75 engages the lower run of the sprocket chain 73. The upper run of the sprocket chain is attached to the vertical plate 31, and this is effected by passing the upper run through a horizontal sleeve 82, rigidly secured to the vertical plate 31. The horizontal sleeve carries a vertical sleeve 83 and a plug 84 is mounted within the sleeve 83, Figure 11, for locking engagement with one link of the chain 73. The plug 84 is moved downwardly by a spring 85 engaged by an upper plug 86, screw threaded within the vertical sleeve 83.

The fabric 27 is woven with the warp 27^a and the filling 27^b in the usual manner, and 27^c are relatively large longitudinally extending strands which are woven into the base of the fabric. The strands 27^c produce floating portions 27^d which are severed at their longitudinal centers, producing W-shaped tufts. The floating portions 27^d are slightly laterally spaced, and these floating portions are arranged in transverse rows inwardly of the selvage edges 27^e of the fabric.

In the operation of the loom, the carriage 30 is held stationary at the right or idling end of the tracks 28, during the weaving period. When the next pair of rows of floating portions are brought to the position to be severed, the leading finger 63' is in alignment with the last row of severed floating portions 27^d, while the trailing finger is in alignment with the unsevered row of floating portions 27^d next rearwardly of such pairs of rows of unsevered floating portions. The prongs 70 are in alignment with the leading pair of unsevered floating portions 27^d. The arms 63 and 63' and the prongs 70 remain upon the selvage 27^e when in the idling or starting position. When the leading pair of rows of unsevered floating portions 27^d move to the severing position, as stated, the carriage 30 is moved forwardly for the width of the fabric. The fingers 63 and 63' first travel over the fabric, in advance of the prongs, the leading arm 63' passing over the row of severed floating portions, and the trailing arm 63 passing over the unsevered row of floating portions, thus holding the fabric flat against curling or puckering, while the prongs 70 pass into the unsevered floating portion 27 of the pair of rows of unsevered floating portions within the recess 65. As the prongs 70 enter the unsevered floating portions 27^d, such floating portions are raised and the continued forward travel of the carriage brings these floating portions into engagement with the rotary cutters 53 and 54 which sever

them at their longitudinal centers. Since the carriage is moving laterally slightly, in the direction of travel to be woven, the cutters keep up with the feed of the fabric and sever the floating portions at their longitudinal centers. After the two rows of floating portions have been completely severed, the carriage is stopped and then moved in the reverse direction to the idling or starting position and remains stationary during the weaving period until the next two rows of floating portions are brought to the severing position in alignment with the prongs 10, at which time the operation is repeated. The present invention is not concerned with the precise means to move the carriage in opposite direction, from the starting or dwelling position and return the same to this position, and any suitable means may be employed to operate the endless sprocket chain 13 for this purpose. We may employ the means shown in the pending application of J. K. McCutchen et al., S. N. 71,898, filed January 21, 1949, for Severing Machine for Looms. The present application is a continuation in part of our copending application S. N. 71,898, filed January 21, 1949.

It is to be understood that the form of this invention herewith shown and described is to be taken as a preferred example of the same and that various changes in the shape, size and arrangement of parts may be resorted to without departing from the spirit of my invention or the scope of the subjoined claims.

Having thus described our invention, what we claim is:

1. In a loom for weaving floating portions in a fabric, a sand roll about which the woven fabric passes, guide means mounted upon the loom near the sand roll, a carriage to travel upon the guide means, means to reciprocate the carriage, and a presser foot mounted upon the carriage to travel over the fabric, said presser foot including a pair of substantially horizontal fingers and a pair of spaced substantially horizontal prongs arranged between the fingers and extending longitudinally of the same, said prongs extending downwardly below the fingers and having their forward ends terminating short of the forward ends of the fingers, and cutting means mounted upon the carriage and coacting with the prongs to sever floating portions thereon.

2. In a loom for weaving floating portions in a fabric, a sand roll about which the woven fabric passes, guide means mounted upon the loom near the sand roll, a carriage to travel upon the guide means, means to reciprocate the carriage, a presser foot mounted upon the carriage to travel over the fabric and including a body portion, a pair of substantially horizontal fingers mounted upon the body portion and laterally spaced to form a recess between them, a pair of substantially horizontal prongs mounted upon the body portion and arranged within the recess and spaced from each other and from the fingers, said prongs extending downwardly below the fingers, the fingers extending forwardly beyond the prongs, said prongs being provided at their tops with longitudinal grooves, rotary cutters mounted upon the carriage and operating within the grooves to sever the floating portions upon the prongs, and means to drive the cutters.

3. In a loom for weaving floating portions in a fabric, a sand roll about which the woven fabric passes, guide means mounted upon the loom near the sand roll, a carriage to travel upon

the guide means, means to reciprocate the carriage, a presser foot mounted upon the carriage to travel over the fabric and including a body portion, substantially horizontal fingers mounted upon the body portion and laterally spaced to form a recess between them, substantially horizontal prongs mounted upon the body portion and arranged within the recess and spaced from each other and from the fingers, said prongs extending downwardly below the fingers, the fingers extending forwardly beyond the prongs, said prongs having upper faces which are longitudinally inclined and extending upwardly toward the body portion, the upper faces having longitudinal grooves, rotary cutters mounted upon the carriage and operating near the grooves to sever the floating portions upon the prongs, and means to drive the cutters.

4. In a loom for weaving floating portions in a fabric, a sand roll about which the woven fabric passes, guide means mounted upon the loom near the sand roll, a carriage to travel upon the guide means, means to reciprocate the carriage, a presser foot mounted upon the carriage to travel over the fabric and including a body portion, a pair of substantially horizontal fingers mounted upon the body portion and laterally spaced to form a recess between them, a substantially horizontal prong mounted upon the body

portion and arranged within the recess and spaced from the fingers, said prong extending downwardly below the fingers, the fingers extending forwardly beyond the prong, said prong having an upper longitudinally inclined face extending upwardly toward the body portion and provided with a longitudinal groove, a rotary cutter mounted upon the carriage and operating near the longitudinal groove to sever the floating portions upon the prong, and means to drive the rotary cutter.

5. In a loom for weaving floating portions in a fabric, a sand roll, a carriage to travel transversely of the fabric being woven and passed about the sand roll, inclined guide means for the carriage to shift the same laterally to keep up with the feed of the fabric as it is woven, a presser foot mounted upon the carriage to travel over the fabric and including substantially horizontal fingers which are spaced to form a passage between them, a substantially horizontal prong arranged between the fingers to enter floating portions upon the fabric, and cutting means mounted upon the carriage to sever the floating portions upon the prong.

6. Means to sever rows of floating portions woven in a fabric upon a loom, said means comprising a presser foot including a body portion, substantially horizontal fingers carried by the body portion and spaced to form a recess between them, a substantially horizontal prong arranged within the recess and secured to the body portion, a power-driven cutter to sever the floating portions upon the prong, and means to move the cutter and presser foot transversely of the fabric.

7. A presser foot to be moved over a fabric having floating portions upon its upper face, said presser foot including a body portion, spaced substantially horizontal fingers carried by the body portion, a substantially horizontal prong mounted upon the body portion between the fingers, the prong having an upper longitudinally inclined face extending upwardly toward the body portion, the upper face having a longitudinal groove and a cutting element operating within the groove.

8. A presser foot to be moved over a woven fabric having transverse rows of floating portions upon its upper face, said presser foot including a body portion, spaced substantially horizontal fingers carried by the body portion, and spaced substantially horizontal prongs arranged between the fingers and secured to the body portion.

9. A presser foot to be moved over a woven fabric having rows of floating portions upon its upper face, said presser foot including a body portion, spaced substantially horizontal fingers secured to the body portion, spaced substantially horizontal prongs secured to the body portion and arranged between the fingers, the prongs extending downwardly below the fingers and the fingers extending forwardly beyond the prongs, the prongs extending beneath the floating portions, and means to sever the floating portions when said floating portions are arranged upon the prongs.

10. A presser foot to be moved over a woven fabric having rows of floating portions upon its upper face, said presser foot including a body portion, a pair of substantially horizontal fingers carried by the body portion and spaced to provide a recess between them, one finger having its lower face disposed at a slight elevation above the lower face of the other finger, substantially horizontal prongs secured to the body portion and arranged within the recess, the prongs extending downwardly below the lower faces of the fingers and the fingers extending forwardly beyond the prongs.

11. In a loom, a guide element over which the fabric passes when being woven with tuft forming strands having floating portions arranged in transverse rows, a track extending longitudinally of the guide element, a carriage to travel upon the track and guided by the track longitudinally of each transverse row of floating portions in succession, to be severed and shifted laterally by such track during its longitudinal movement, a power operated cutter mounted upon the carriage and movable with relation thereto to sever the floating portions in the row in succession, and driving means connected with the carriage to shift the same longitudinally of the track.

12. In a loom, a guide element over which the fabric passes when being woven with tuft forming strands having floating portions arranged in transverse rows, a track extending longitudinally of the guide element, a carriage to travel upon the track and guided by the track longitudinally of each transverse row of floating portions in

succession to be severed and shifted laterally by such track during its longitudinal movement, a presser foot mounted upon the carriage to engage the top of the fabric to pass beneath the floating portions in the transverse row, said presser foot having a part to raise the floating portion, a rotary cutter mounted upon the carriage and arranged near the raised portion of the presser foot to sever the floating portions upon the raised part of the presser foot, means to rotate the cutter, and driving means connected with the carriage to move it longitudinally of the track while the fabric is being woven.

13. In a loom, a guide element over which the fabric passes when being woven with tuft forming strands having floating portions arranged in transverse rows, a track extending longitudinally of the guide element, a carriage to travel upon the track to be guided by the track longitudinally of each transverse row of floating portions in succession to be severed and shifted laterally by such track during its longitudinal movement, a presser foot mounted upon the carriage and arranged to contact with the upper face of the fabric at a point spaced from the guide element, the presser foot including a longitudinally inclined raised portion having a groove, the presser foot being adapted to pass beneath the floating portions in succession in the row, a rotary cutter mounted upon the carriage and having its cutting edge operating within the groove, means to drive the rotary cutter, and driving means connected with the carriage to move it longitudinally of the track while the fabric is being woven.
